UNITED STATES PATENT OFFICE.

GEORGE ERNEST STUDDY, OF LONDON, ENGLAND.

DESIGN FOR A TOY ANIMAL.

Application filed March 31, 1928, Serial No. 26,032, and in Great Britain January 11, 1928. Term of patent 14 years.

To all whom it may concern:

Be it known that I, GEORGE ERNEST STUDDY, a British subject, whose post-office address is Granville House, Arundel Street, Strand, London, England, have invented a new, original, and ornamental Design for Toy Animals, of which the following is a specification, reference being had to the accompanying drawings, forming part thereof.

In the drawings, Figure 1 is a front view and Figure 2 a side view of a toy animal, showing my new design.

I claim:

The ornamental design for a toy animal, as shown.

GEORGE ERNEST STUDDY.
